UNITED STATES PATENT OFFICE

2,579,990

BOBBY PIN SPREADING DEVICE

Ruth K. Weaver, Chicago, Ill., assignor to Gaylord Products, Incorporated, Chicago, Ill., a corporation of Illinois

Application May 15, 1948, Serial No. 27,352

9 Claims. (Cl. 29—235)

1

This invention relates to improvements in a bobby pin opening device, and is more particularly concerned with the provision of a device of this type adapted for use in transferring bobby pins from a notched rod onto an oven wire. After bobby pins have been formed from wire, they must be tempered and finished. To facilitate the tempering and finishing operations, the bobby pins are arranged in spaced parallel relation upon a suitable wire, referred to as an oven wire. It is an object of the present invention to provide a relatively simple device adapted for use in mounting bobby pins upon oven wires for subsequent manufacturing operations, such as tempering, japping, varnishing, drying, etc.

This invention further contemplates the provision of a device adapted for use in simultaneously opening a relatively large group of bobby pins arranged in spaced parallel relation along a notched rod, and for inserting an oven wire between the legs of the group of bobby pins. The notched rod is then removed and the legs of the bobby pin are permitted to move into clamping engagement upon the oven wire.

This invention further contemplates the provision of a bobby pin spreading device which is relatively simple and inexpensive to manufacture, and reliable in operation.

This invention embodies other novel features, details of construction and arrangement of parts, which are hereinafter set forth in the specification and claims, and illustrated in the accompanying drawings wherein:

Fig. 1 is a side elevational view illustrating a bobby pin opening device embodying features of this invention.

Fig. 2 is a top plan view of same.

Fig. 3 is a longitudinal sectional view taken along the line 3—3 of Fig. 2.

Fig. 4 is a transverse sectional view taken along the line 4—4 of Fig. 2.

Fig. 5 is a fragmentary transverse sectional view, corresponding to Fig. 4, showing the position of parts at the termination of the operation of positioning an oven wire between the legs of a group of bobby pins.

Fig. 6 is a detail plan view illustrating a group of bobby pins mounted upon an oven wire.

Fig. 7 is a detail sectional view taken along the line 7—7 of Fig. 6.

Fig. 8 is a detail plan view illustrating a group of bobby pins as arranged in spaced parallel relation along a notched rod or bar prior to transfer of the bobby pins onto an oven wire.

Referring now to the drawings for a better

2

understanding of this invention, the bobby pin spreading device is shown as comprising a pair of side frame members 6—6 secured in spaced parallel relation by a cross plate 7 and a top plate 8. The side members and transverse members, forming the frame 9 of the bobby pin spreading device, are adapted to be supported upon a suitable work table 11.

A pair of arms 12—12 have their inner ends 10 secured to their respective frame members 6—6 and their outer ends projecting toward the operator to receive and support the ends of a notched rod 13. A plurality of bobby pins 14 are mounted on the notched rod 13 and are moved into spaced parallel relation within their respective notches 16 by means of a ring 17 mounted upon the thumb of the operator. After the bobby pins 14 are equally spaced along the notched rod 13, the rod and bobby pins are 20 mounted upon the forward end of the top plate 8, as illustrated in Fig. 4 of the drawings. It will be noted that the loop end of the bobby pins 14 are disposed against an abutment flange 18 provided on the forward edge of the top plate 8, and that the uncrimped legs of the bobby pins have their free ends engaged against an abutment wall 19 formed on the top plate 8, the abutment wall 19 being of a depth equal to the thickness of the free ends of the bobby pins.

30 A push plate 21 is guided for reciprocable movement along the upper surface of the top plate 8 by means of guide blocks 22—22 disposed in slots 23—23 formed in the top plate. The blocks 22—22 are secured to the push plate 21 35 by means of cap screws 24. A bearing rod 24 is secured in apertures 26—26 formed in the guide blocks 22—22 and has its ends engaged by tension springs 27—27 leading to posts 28—28 provided on arms 29—29 mounted on the top plate 8. The tension springs 27—27 act to yieldably resist forward movement of the push plate 21 relative to the top plate 8.

35 A pair of connecting links 31—31 are journaled on the bearing rod 24 and extend outwardly for pivotal engagement on the ends of a cross rod 32 secured at one end of a lever 33. The lever 33 is journaled intermediate its ends on a bearing pin 34 provided on a bifurcated bracket 36 secured to the cross plate 7. A foot pedal 37 is mounted on one end of an arm 38 which has its other end adjustably secured by means of cap screws 39 to the lower end of the lever 33. A tension spring 41 has its one end connected to a pin 42 provided on the cross plate 7, and its other 50 end secured to a bracket 43 provided on the lever

33. The tension spring 41 serves to yieldably resist pivotal movement of the lever 33 in a clockwise direction, as illustrated in Fig. 1.

A lifting plate 46 is secured to a cross shaft 47 journaled at its ends in bearing blocks 48-48. The bearing blocks 48-48 are guided for common reciprocable movement along the upper surface of the top plate 8 by means of guide bars 49-49 disposed in recesses 51-51 formed in the guide blocks. Each guide bar 49 10 is secured in spaced parallel relation to the top plate 8 by means of spacing blocks 52 and 53 and bolts 54. Each bearing block 48 and its respective spacing block 52 is formed with opposing recesses at 56 and 57, respectively, to receive the ends of a compression spring 58 which acts to yieldably resist movement of its respective bearing block 48 toward its spacing block 52. One end of a tension spring 61 is secured at 62 to a bearing block 48, the opposite end of 20 the spring being secured to an arm 63 provided on the cross shaft 47. The tension spring 61 acts to yieldably resist counterclockwise movement of the shaft 47, as viewed in Figs. 1, 4, and 5. Each bearing block 48 is also provided with 25 a catch arm 64 to be engaged by a pin 66 provided on the push plate 21. During the rearward movement of the push plate 21, it will be noted that the pins 66-66 engage their respective arms 64-64 to move the bearing blocks 30 48-48 rearwardly against the action of the compression springs 58-58.

In transferring a group of bobby pins 14 from the notched rod 13 to an oven wire 71, the transverse portion 72 of the oven wire is positioned 35 against the forward edge of the push plate 21 with the side arms 73 of the oven wire disposed under a pair of flat resilient springs 74-74. The transverse portion 72 of the oven wire is held 40 in position against the forward edge of the push plate 21 by means of the lifting plate 46, as illustrated in Fig. 4.

The push plate 21 is moved in a forward direction by manual pressure exerted by the operator against the foot pedal 31 which causes the lever 33 to act through the connecting links 31-31, bearing rod 24, and guide blocks 22-22. During forward movement of the push plate 21, the lifting plate 46 maintains its position relative to the push plate to cause its bevelled forward edge 76 to engage between the legs of the bobby pins 14. Further forward movement of the push plate 21 causes the lifting plate 46 to move the crimped legs of the bobby pins away from the uncrimped legs and permits the forward edge of the push plate to insert the transverse portion 72 of the oven wire 71 between the legs of the bobby pins, as illustrated in Fig. 5.

When the operator releases the foot pedals 37, the tension springs 27 and 41 act to move the push plate 21 toward its rearward position. As the push plate 21 travels rearwardly, the pins 66-66 act through their respective arms 64-64 to move the bearing blocks 48-48 rearwardly against the action of the compression springs 58-58. After withdrawal of the notched bar 13, the group of bobby pins 14 is mounted in spaced parallel relation upon the oven wire 71 in the manner illustrated in Figs. 6 and 7 in the drawings. The oven wire with its bobby pins mounted thereon is then delivered to other departments for subsequent finishing operations, such as tempering, japanning, varnishing, carding, etc.

While this invention has been shown in but one form, it is obvious to those skilled in the art that it is not so limited but is susceptible of various changes and modifications without departing from the spirit and scope of the claimed invention.

I claim as my invention:

1. In a device for mounting a group of bobby pins upon an oven wire, a supporting plate, a rod formed with notches at spaced intervals to position a group of bobby pins in spaced parallel relation upon said plate, a lifting plate mounted above said supporting plate, a pusher plate mounted for reciprocable movement along the upper surface of said supporting plate to coact with said lifting plate to spread the legs of a group of bobby pins and to insert an oven wire therebetween, and means to actuate said lifting plate and pusher plate.

2. In a device for mounting a group of bobby pins upon an oven wire, a supporting plate, a rod formed with notches at spaced intervals to position a group of bobby pins in spaced parallel relation upon said plate, a lifting plate mounted above said supporting plate, a pusher plate mounted for reciprocable movement along the upper surface of said supporting plate to coact with said lifting plate to spread the legs of a group of bobby pins and to insert an oven wire therebetween, and means to reciprocate said pusher plate.

3. In a device for mounting a group of bobby pins upon an oven wire, a supporting plate, a rod formed with notches at spaced intervals to position a group of bobby pins in spaced parallel relation upon said plate, a lifting plate mounted above said supporting plate, a pusher plate mounted for reciprocable movement along the upper surface of said supporting plate to coact with said lifting plate to spread the legs of said group of bobby pins and to insert an oven wire therebetween, means to reciprocate said pusher plate, resilient means acting to urge said lifting plate forward into engagement between the legs of a group of bobby pins, and means operable responsive to rearward movement of said pusher plate to move said lifting plate rearwardly to its inoperative position.

4. In a device for mounting a group of bobby pins upon an oven wire, a supporting plate, a rod formed with notches at spaced intervals to arrange a group of bobby pins in spaced parallel relation upon said supporting plate, a pusher plate guided for reciprocable movement along said supporting plate to insert an oven wire between the legs of said group of bobby pins, and a lifting plate disposed above said pusher plate to coact with the latter in opening the legs of said group of bobby pins.

5. In a device for mounting a group of bobby pins upon an oven wire, a supporting plate, a rod formed with notches at spaced intervals to arrange a group of bobby pins in spaced parallel relation upon said supporting plate, a pusher plate guided for reciprocable movement along said supporting plate to insert an oven wire between the legs of said group of bobby pins, a lifting plate disposed above said pusher plate to coact with the latter in opening the legs of said group of bobby pins, and a pair of bearing blocks guided for common reciprocable movement along said supporting plate, said lifting plate being secured to a shaft journaled at its ends in said bearing blocks.

6. In a device for mounting a group of bobby

pins upon an oven wire, a supporting plate, a rod formed with notches at spaced intervals to arrange a group of bobby pins in spaced parallel relation upon said supporting plate, a pusher plate guided for reciprocable movement along said supporting plate to insert an oven wire between the legs of said group of bobby pins, a lifting plate disposed above said pusher plate to coact with the latter in opening the legs of said group of bobby pins, a pair of bearing blocks guided for common reciprocable movement along said supporting plate, said lifting plate being secured to a shaft journaled at its ends in said bearing blocks, and means operable responsive to reciprocable movement of said pusher plate to reciprocate said bearing blocks.

7. In a device for mounting a group of bobby pins upon an oven wire, a supporting plate, a rod formed with notches at spaced intervals to arrange a group of bobby pins in spaced parallel relation upon said supporting plate, a pusher plate guided for reciprocable movement along said supporting plate to insert an oven wire between the legs of said group of bobby pins, a lifting plate disposed above said pusher plate to coact with the latter in opening the legs of said group of bobby pins, a pair of bearing blocks guided for common reciprocable movement along said supporting plate, said lifting plate being secured to a shaft journaled at its ends in said bearing blocks, means operable responsive to reciprocable movement of said pusher plate to reciprocate said bearing blocks, and means to limit the forward travel of said bearing blocks.

8. In a device for mounting a group of bobby pins upon an oven wire, a supporting plate, a rod formed with notches at spaced intervals to arrange a group of bobby pins in spaced parallel relation upon said supporting plate, a pusher plate guided for reciprocable movement along said supporting plate to insert an oven wire between the legs of said group of bobby pins, a lifting plate disposed above said pusher plate to coact with the latter in opening the legs of said group of bobby pins, a pair of bearing blocks

45

guided for common reciprocable movement along said supporting plate, said lifting plate being secured to a shaft journaled at its ends in said bearing blocks, means operable responsive to reciprocable movement of said pusher plate to reciprocate said bearing blocks, means to limit the forward travel of said bearing blocks, and means to hold said bearing blocks in their forward position during subsequent forward movement of said pusher plate.

9. In a device for mounting a group of bobby pins upon an oven wire, a supporting plate, a rod formed with notches at spaced intervals to arrange a group of bobby pins in spaced parallel relation upon said supporting plate, a pusher plate guided for reciprocable movement along said supporting plate to insert an oven wire between the legs of said group of bobby pins, a lifting plate disposed above said pusher plate to coact with the latter in opening the legs of said group of bobby pins, a pair of bearing blocks guided for common reciprocable movement along said supporting plate, said lifting plate being secured to a shaft journaled at its ends in said bearing blocks, means operable responsive to reciprocable movement of said pusher plate to reciprocate said bearing blocks, means to limit the forward travel of said bearing blocks, and resilient means to hold said bearing blocks in their forward position during subsequent forward movement of said pusher plate.

RUTH K. WEAVER.
